INVENTOR

UNITED STATES PATENT OFFICE.

DENNIS SWEENEY, OF FARMINGDALE, NEW YORK.

DESIGN FOR A NECKLACE.

Application filed October 15, 1925. Serial No. 15,123. Term of patent 7 years.

To all whom it may concern:

Be it known that I, DENNIS SWEENEY, a citizen of the United States, residing at Nassau County Sanatorium, Farmingdale, Long Island, in the county of Nassau and State of New York, have invented a new, original, and ornamental Design for Necklaces, of which the following is a specification, reference being had to the accompanying drawing, forming part thereof.

I claim:

The ornamental design for a necklace, as shown.

DENNIS SWEENEY.
